US00D936671S

(12) **United States Design Patent** (10) **Patent No.:** **US D936,671 S**
Jeon et al. (45) **Date of Patent:** **** Nov. 23, 2021**

(54) **DISPLAY SCREEN OR PORTION THEREOF WITH GRAPHICAL USER INTERFACE**

(71) Applicant: **SAMSUNG ELECTRONICS CO., LTD.**, Suwon-si (KR)

(72) Inventors: **Jinhee Jeon**, Seongnam-si (KR); **Jieun Yang**, Busan (KR)

(73) Assignee: **SAMSUNG ELECTRONICS CO., LTD.**, Gyeonggi-Do (KR)

(**) Term: **15 Years**

(21) Appl. No.: **29/632,958**

(22) Filed: **Jan. 11, 2018**

(30) **Foreign Application Priority Data**

Oct. 23, 2017 (KR) 30-2017-0049123

(51) **LOC (13) Cl.** **14-04**

(52) **U.S. Cl.**

USPC **D14/486**

(58) **Field of Classification Search**

(57) **CLAIM**

The ornamental design for a display screen or portion thereof with graphical user interface, as shown and described.

DESCRIPTION

The FIGURE is a front view of a display screen or portion thereof with graphical user interface showing our new design.

The outermost perimeter illustrated by a dashed broken lines represents the display screen or portion thereof and forms no part of the claimed design.

The remaining dashed broken lines shown in the drawing illustrate portions of the graphical user interface that form no part of the claimed design.
